UNITED STATES PATENT OFFICE.

HENRY V. WALKER, OF NEWARK, NEW JERSEY.

PROCESS FOR NITRATING CELLULOSE.

Original application filed May 20, 1920, Serial No. 382,810. Divided and this application filed September 23, 1922. Serial No. 589,961.

To all whom it may concern:

Be it known that I, HENRY V. WALKER, a citizen of the United States, residing in Newark, county of Essex, State of New Jersey, have invented a certain Improvement in Processes for Nitrating Cellulose, of which the following is a specification.

The present invention has relation to an improvement in process for nitration of cellulose and the like, whereby the same is rendered continuous, efficient, safe and economical.

This is a division of my application for patent filed May 20th, 1920, Serial No. 382,810, wherein the apparatus herein described is claimed.

In the manufacture of nitro-cellulose or gun-cotton, the raw cotton is first subjected to the action of sulphuric and nitric acids in suitable proportion to produce the necessary nitrating reaction. The excess acid is then removed so far as possible by mechanical action, and this process is finally completed by a series of boiling and washing operations to render the product thoroughly stable.

It has been common, hitherto, to carry on the nitrating process in the basket of a centrifugal separator, and, after the mixture has stood for a sufficient time to complete the reaction, the separator is set running so as to accomplish the mechanical extraction, of the excess free acid. The boiling and washing processes follow this centrifugal extraction process.

By thus using the centrifugal machine as a dipping chamber, a good deal of time is lost, because the machine is prevented from carrying out its proper natural function as an extractor during the time occupied by the chemical reaction. The same waste of time is involved where the dipping is done in a separate chamber which is discharged into the waiting centrifugal machine after completion of each reaction.

The present invention involves a process wherein a succession of charges of mixed cotton (or equivalent substance) is conveyed in a continuous series by intermittent movements, suitably timed, from a charging point to the point of extraction, and wherein the extracting process on the one hand and the charging process on the other hand are accomplished simultaneously at opposite ends of the moving series, during the

time intervals between the successive forward movements of the charges. It is a novel characteristic of my improved process that, during the forward movement of the material, it is given a gentle agitation. 60

By this plan it is clear that a sufficient time can be given to carry out the nitration of each charge while it is moving forward through the series of allotted positions; while, on the other hand, the extracting machine is kept busy all the time, being emptied after each extraction and placed in readiness for the next charge in the series. 65

Another important advantage presented by this process is found in the fact that it admits of automatic control of the time of nitration. In prior systems the time of nitration is subject to the control of the operator, but in the present system this is not the case as the first charge cannot leave 70 the dipping series until a number (preferably four) subsequent charges have been introduced into the series. Sufficient time for nitration is thus insured for every charge. 75

The apparatus forming a part of this invention has the advantage of great simplicity in construction and operation—particularly in regard to the acid piping, and the disposition of fumes. 80

A form of apparatus for carrying out this process is illustrated in the accompanying drawings, wherein Figure 1 is a diagrammatic side elevation, partly in section, of the complete apparatus, Figure 2 is an end view of the nitrating cylinder viewed from the left in Figure 1, Figure 3 is a sectional view of the apparatus on the line 3-3 in Figure 1, and Figure 4 is a detail view of the discharge end of the nitrating cylinder. 85

The nitrating cylinder 10 is furnished with an internal partition 11 extending in a wide spiral from end to end of the cylinder. The outer edge of this spiral or helical partition is closely united to the interior of the cylinder, preferably by welding; and it thus divides the cylinder into four chambers or compartments. Central openings 12 are formed in the successive spirals, serving both to facilitate construction and to make it possible to carry off from all the compartments the fumes which are normally disengaged during nitration. 95

At the charging end of the cylinder, a door 13 is furnished, through which the operator may introduce the cotton and mix it, 100 105 110

by means of an iron fork, with the heated acids which may run in through the piping 14. The discharging end of the cylinder 10 is provided with a discharge chute 15.

5 Suitable means are employed whereby the cylinder and its internal partition may be revolved upon their common axes; and for this purpose, in the form shown, friction bands 16 and 17 are provided which rest 10 upon friction wheels 18, 19, near each end.

The wheels 19 are fixed to a common driving shaft 20, by means of which they are made to drive the cylinder 10. Any motive means (automatic or otherwise) may 15 be used for driving the shaft 20; as, for instance, an electric motor 21, acting through the belt 22, and clutch 23. This clutch is operated by the handle 24, so that the revolution of the cylinder may be controlled by 20 the operator.

At the discharge end of the cylinder 10 is placed the centrifugal acid extractor 25 which may be of any well known form, the details of which need no illustration. It is 25 preferred to employ the type of extractor in which a removable basket 26 is used, which can be removed and replaced by suitable mechanism, as, for instance, the pneumatic lift 27.

30 Just beyond the extractor 25 is placed the washing tank 28 for removing the excess free acid from the cotton which leaves the extractor. This is preferably provided with a raised perforated bottom 29, from under 35 which the water may be drawn off through the drain 30.

A fume-hood 31 extends over the extractor 25 and over the front end of the tank 28; and fume pipes 32, 33 extend out from 40 under this hood, through which the fumes are drawn off in a well known manner. The motor for driving the centrifugal acid extractor is indicated at 34.

The improved process is carried out in this 45 apparatus as follows—

The heated acids are introduced by the operator into the first nitrating compartment, together with the proper quantity of cotton. The charge thus formed fills this 50 charging compartment up to a level somewhat under the lower edge of the door 13; through which the operator can manipulate the charge by means of a suitable tool. The mixture being accomplished, the cylinder is 55 rotated through a single revolution and is then stopped. This results in transferring

the entire charge to the second compartment, leaving the first or charging compartment empty, and ready for a new charge. At the same time, the friction of the rotating walls 60 of the helix serves to promote a mild agitation in the mixture.

The operations thus far described are repeated indefinitely, with the result that each charge in succession is finally brought into 65 the last compartment, in which, as shown at 35 in Figure 4, the helix is so shaped as to lift the charge to the level of the chute 15, through which it falls by gravity into the removable basket 26 of the centrifugal extractor. 70

Between successive revolutions of the cylinder 10, and therefore between successive deliveries of charges through the chute 15, the extractor 25 is operated, emptied by removal of the basket 26 whose contents are 75 dumped into the tank 28, and prepared for a new charge by return of the basket to its place. At the same time the first compartment is being charged, as already described. 80

It will be seen that, by this arrangement, there is a series of successive charges moving step by step toward the extractor which is thus kept always in operation, except during the necessary removal and return of the inner basket. As each charge has to move through the whole series of positions before being delivered to the extractor, ample time for nitration is provided. This time can be regulated by the number of positions and the time it takes to charge and to extract. 85 In practice, it has been found that good results are achieved by the use of four compartments and four positions of rest, but, of course, the invention is not limited to any 90 given number of positions. 95

What is claimed is—

The process of nitrating cotton and the like which comprises the following steps, 100 namely:—conveying a succession of separate charges of mixed cotton and acids from a charging point to an extracting point by a succession of intermittent movements accompanied by a smooth frictional action on the charges causing gentle agitation during 105 movement forward and subjecting each charge in turn to the extraction process at the end of its travel.

In testimony whereof I have hereto set my hand on this 18th day of September, 110 1922.

HENRY V. WALKER.
